UNITED STATES PATENT OFFICE.

EDWARD J. BLAIR, OF CHICAGO, ILLINOIS.

SUPPORT FOR THIRD RAILS.

1,028,668.

Specification of Letters Patent.

Patented June 4, 1912.

Application filed September 2, 1911. Serial No. 647,377.

To all whom it may concern:

Be it known that I, EDWARD J. BLAIR, a citizen of the United States of America, and a resident of Chicago, county of Cook, State of Illinois, have invented certain new and useful Improvements in Supports for Third Rails, of which the following is a specification.

The main objects of this invention are to provide an improved, simple and inexpensive form of support for the third rails of electric railways, which is constructed so as to effectively insulate the third-rail from all of its surroundings; and to provide improved means for securing the rail in place on its support.

An illustrative embodiment of this invention is shown in the accompanying drawings, in which:—

Figure 1 is a side elevation of a third-rail support showing the rail in position thereon. Fig. 2 is a sectional elevation taken on the line A—A of Fig. 1. Fig. 3 is a plan view of the support, the lugs of the clamping means being shown upstanding, as indicated by the dotted lines in Fig. 2.

In the construction shown in the drawings, the device comprises a cylindrical standard formed of hard wood or other suitable insulating material, the lower portion of which has a downwardly flaring taper to provide an enlargement 2 to which the base 3 is secured. The base 3 comprises a plate or ring 4, provided with a plurality of apertures 5 for the reception of bolts or other fastening means for securing it to a foundation member or other supporting structure. An upstanding flange 6 tapered to fit the flared end 2 of the standard is integrally formed on the plate 4.

A crown or cap 7 fits over the upper end of the standard 1 and is secured thereto by means of the pin or bolt 8. The rail 9 is adapted to rest on the cap 7 between shoulders or lugs 10 integrally formed on opposite sides of the cap 7 and spaced apart longitudinally of the rail. A slot 11 extends through the cap 7 between the spaced shoulders 10 in a direction transverse to the rail.

A bar 12 formed of wrought metal is inserted through the slot 11 and has its ends 13 bent upwardly and inwardly to engage and hold the base portion 14 of the rail 9, so as to secure the rail to the cap 7.

In order to prevent water from short cir-

cuiting the rail 9 to the base 3 or any of its surroundings, an annular skirt 15 is integrally formed on the cap 7, below its connection to the standard 1.

The device is assembled by passing the base 3 downwardly over the standard 1 and driving the enlarged end 2 of the standard into a snug fit with the tapered flange 6, the dimensions of the tapered part of the standard being preferably such that when it is driven home in the base, its bottom will be substantially flush with or project slightly below the bottom of said base. The cap 7 is then placed on the standard 1 and secured by a pin or rivet 8. The bar 12 is inserted into the slot 11, and the ends 13 thereof bent upwardly to the position shown in dotted outline in Fig. 2. When a row of the insulators has been set up, the rail 9 is placed in position so as to rest on the caps 7 and the ends 13 of the clamp bars are bent down to the position shown in full lines in Fig. 2. The lugs 10 prevent lateral shifting of the rail.

Although but one specific embodiment of this invention is herein shown and described, it will be understood that numerous details of the construction shown may be altered or omitted without departing from the spirit of this invention, as defined by the following claims.

I claim:—

1. A support for third rails, comprising a standard, a cap secured to the upper end thereof and adapted to support a rail thereon, said cap having a slot extending therethrough transversely of the rail, and a clamping member adapted to be inserted into said slot and to have the ends thereof bent over to engage the rail.

2. A support for third rails, comprising a standard, a cap secured to the upper end thereof and adapted to support a rail thereon, said cap having a slot extending therethrough transversely of the rail, a clamping member adapted to be inserted into said slot and to have the ends thereof bent over to engage the rail, and shoulders at opposite sides of said clamping member adapted to abut against the edges of the rail.

3. A support for third rails, comprising a standard, a cap secured to the upper end of said standard, and adapted to support a rail thereon, spaced integral shoulders on opposite sides of said cap adapted to abut

against the edges of the rail, said cap having a slot extending therethrough between said shoulders, and a clamping member adapted to be inserted into said slot and to have the 5 ends thereof bent over to engage and secure the rail.

Signed at Chicago this 30th day of Au-
gust 1911.

EDW. J. BLAIR.
